DESIGN FOR A FISH LURE

Andy Dolak, Flint, Mich.

Application October 10, 1947, Serial No. 141,862

Term of patent 3½ years

(Cl. D31—4)

To all whom it may concern:

Be it known that I, Andy Dolak, a citizen of the United States, residing at Flint, in the county of Genesee and State of Michigan, have invented a new, original, and ornamental Design for a Fish Lure, of which the following is a specification, reference being had to the accompanying drawings, forming a part thereof.

Figure 1 is a side view of a fish lure, showing my new design.

Figure 2 is a front end view.

Figure 3 is a rear end view.

Figure 4 is a top plan view.

I claim:

The ornamental design for a fish lure, as shown.

ANDY DOLAK.
